RAILWAY CAR STRUCTURE

Ambrose C. Moore and Axel Wasberg, Chicago,
Ill., assignors to Chicago Railway Equipment
Company, Chicago, Ill., a corporation of Illi-
nois

Application October 30, 1933, Serial No. 695,858

18 Claims. (Cl. 189—46)

This invention relates to flush type sliding doors, particularly for use in railway rolling stock, in which the door at the end of its sliding movement in a closing direction must be moved transversely of its main line of movement to cause it to closely fit within the doorway.

The desirability of inset or flush doors for freight cars has been recognized, particularly in refrigerator cars and grain cars in which a tight door is essential. Flush doors when closed are more stably mounted, are less susceptible to damage by being sideswiped, and are more resistant to unauthorized tampering than ordinary sliding doors which at all times are carried on tracks extending along the outside of the car wall.

In effecting the necessary transverse movement of sliding doors of the flush type, the doors are frequently lifted or swung free of their bearings and in the closed position rest on the threshold of the doorway. This arrangement causes sticking of the door in the doorway and requires heavy operating mechanism to support the weight of the door during transverse movement.

One object of the present invention is to provide improved means for effecting the transverse movement of a railway car flush door whereby sticking of the door is prevented.

Another object is to provide novel framing structure for a flush door and doorway which, when the door is in its closed position, forms improved weather and dust sealing means.

Another object is to provide a sliding door structure which may be advantageously used in railway box cars and in which the construction is substantially simplified and strengthened over previous car door structures.

These objects and others are attained substantially by the structures illustrated in the accompanying drawings, in which—

Figure 1 is a partial view of a railway box car showing a sliding door applied thereto.

Figures 2, 3, 8 and 9 are detail vertical transverse sectional views taken respectively on the lines 2—2, 3—3, 8—8 and 9—9 of Figure 1 and showing the door in the full closed position.

Figures 2a, 3a, 8a and 9a are sections corresponding respectively to Figures 2, 3, 8 and 9 but showing the door in partially open position.

Figures 4, 5, 6, 7 and 10 are detail horizontal sectional views taken on the corresponding section lines of Figure 1.

Figures 11 and 12 are vertical transverse sectional views showing a modified door and door-

way construction and corresponding respectively to Figures 2a and 3a.

Figures 13, 14, 15, 16 and 17 are detail horizontal sectional views of the same.

Figure 18 is a detail horizontal sectional view showing the forward edge assembly of still another form of door and door post construction.

Figure 19 is a similar sectional view of the same but taken through the rear edge of the door and door post.

Figures 20 and 21 are detail vertical transverse sections of the construction shown in Figures 18 and 19 but taken respectively through the top and bottom edges of the door and the adjacent wall members.

Figures 22 and 23 are detail vertical transverse sectional views corresponding to Figures 3 and 3a and showing still other modifications.

Figures 1 to 10 of the drawings illustrate a portion of a railway box or house car side wall with a pair of substantially Z-section door posts 2 and 3 defining a door opening and arranged to receive the door in a position substantially flush with the car side wall. Adjacent the lower edge of the door and extending along the side sill 4 is a bearing track 5 supported from the side sill by means of brackets 6. Extending along the top edge of the door are guide track members 7—7a riveted to the Z-section cornice plate 8. The tracks 5 and 7 extend substantially from the front door post 2 longitudinally beyond the rear door post 3 in the usual manner.

Supported on the lower bearing track 5 is a sliding door including Z-section front and rear frame members 9 and 10, similarly shaped top and bottom members 11 and 12, panels 13, which are preferably of metal, and horizontal brace beams 14. The bottom Z frame member 12 cooperates with a slightly offset plate 15 also secured to the lower edge of the door paneling to form a housing for the ball bearings 16 held in spaced relation by a cage 17. The cage 17 fits loosely between the sides of the housing so that the balls are permitted a limited amount of transverse rolling without sliding.

The upper and lower forward corners of the door are reinforced by gusset members 18 and 19, the former of which includes as a rigid part thereof the projecting retainer 20 having a door post abutment 20a. The lower corner gusset 19 includes a projecting door guide 21 which overlaps the end of the bearing housing 12, 15, thereby serving as a bearing stop.

At the forward upper and lower corners of the doorway framing are provided guide castings 25

and 26 secured to the door post 2 and to the cornice plate and side sill respectively. These guides have surfaces 27 and 28, respectively, inclined to the plane of the door for cooperating with the 5 upper corner 9b of the door and the projection 21 on the lower corner thereof to guide the forward edge of the door inwardly when it is being closed.

At the upper and lower rear corners of the door are provided corner gussets 30 and 31 which 10 respectively include as rigid parts thereof the perforated bosses or bearings 32 and 33 which rotatably mount the operating bar 34. Gusset 31 also includes an inward projection closing the end of bearing housing 12, 15 and forming a bearing 15 carriage stop. At the ends of the bar 34 are cranks 35 and 36 pivotally mounting the offset retainers 37 and 38 (Figures 8 to 9a) associated respectively with and slidable along the upper and lower tracks 7 and 5. The upper retainer 37 20 has a pair of jaws which loosely receive therebetween the upper track 7 (Figure 8) and the lower retainer 38 has depending flanges 38a and 38b overlapping the sides of the lower track 5 (Figure 9). In order to accommodate the inner 25 flange 38b of the lower retainer and permit it to clear the side wall of the car, the portion of the track 5 located to the right of the rear door post 3 is coped, as best shown in Figures 7 and 10. The remainder of the track 5 extends, as at 5a, 30 substantially within the door opening and above the portion of side sill 4 beneath the door opening.

The operating rod 34 is provided with a handle 39 whereby the rod 34 and cranks 35 and 36 may 35 be rotated on retainers 37 and 38 as pivoting centers to move the rear portion of the door transversely of the car side. Handle 39 has a slot 40 for receiving the staple 41 projecting from a plate 42 secured to the face of the door. Pivoted to the plate 42 is an arm 43 including a depending finger 44 disposed to pass through the 40 staple 41 to lock the arm 39 in position. The lock may be secured against unauthorized tampering by means of a seal through perforated lugs 45 and 46.

45 The door will rest at all times upon the lower track 5, the balls 16 moving transversely thereon during movement of the door to and from the flush position within the inset doorway. The inwardly extending portion 5a of this track also 50 serves to break the passage of dust and other material which might otherwise work up through the crevice between the bottom of the door and the opposing doorway frame (see Figure 3). Since the door is at all times fully supported on 55 its bearings upon the track 5, sticking thereof, particularly in the closed position, will be eliminated. This feature constitutes a substantial improvement over the forms of flush doors now generally in use in which the door in the closed position is carried on the threshold of the doorway instead of on the bearing track.

60 The front lower door gusset 19 includes a bracket 23 (Figure 3) which pivotally mounts a retainer member 24 having a hook engaging the vertical flange of track 5 to limit outward movement of the adjacent portion of the door as indicated in Figure 4. The inner flange 11a of the door top frame member 11 cooperates with track 7 (Figure 2a) to limit outward movement of the 65 adjacent portion of the door.

70 The horizontal upper edge of the doorway is closed against the ingress of moisture, dust and other foreign matter by the contact of the door panel 13 with the door opposing web 7b, as shown 75 in Figure 2. The lower edge of the doorway is

closed by the engagement of offset plate 15 with the floor edge 47 (Figure 3). As previously explained, the wide track 5 assists in sealing the bottom of the doorway. The inner flanges 2a and 3a of the door posts 2 and 3 extend from the webs of the Z bars parallel to the door and then outwardly to form, with the webs, three-sided pockets 49 and 49a. The edges of these flanges abut the door when the latter is in closed position. Secured to a portion of the web of door post 2 10 and spaced from the inner flange thereof is a Z-shaped strip 48 (Figure 5) projecting towards the edge of the door. In the closed position of the door, forward edge 9a thereof extends between flange 2a and strip 48. The forward edge 15 of the door edging 9 cooperates with this flange and strip to form a pair of dust and weather repelling pockets 49 and 50. Member 48 may be omitted, if desired, and the single pocket 49 relied upon as a weather and dust seal. The pockets 20 49 and 49a preferably will be opened at the bottom between the side sill 4 and track 5 and form an outlet for trapped moisture and dust. An angle 25 29 (Figure 6) may be applied to the rear edge of the door to form an additional seal at that point.

Figures 11 to 17, inclusive, illustrate other edge sealing means which may be used advantageously in refrigerator cars. Figure 11 shows the cornice plate 54 fitted with a wooden beam 54a with its lower forward corner cut out to receive the top 30 edge member 52 of the door 51. A resilient insulating tubular strip 53 formed of canvas, rubber or similar material, is secured to the outwardly facing portion of beam 54a. The strip mounting face of the beam and the corresponding flange 35 52a of the door upper edge member 52 are, respectively, concave and convex in transverse section to cooperate more effectively in compressing the insulation 53 in providing a tight joint.

Figure 13 shows the end of beam 54a abutting 40 the Z-bar post 56 and overlying the upper end of the forward edging 51 of the door and the elements cooperating therewith which are more clearly detailed in Figure 14 in which the wooden filler 56a is applied to the outer face of the Z-bar 45 56 and mounts the tubular insulation 55. The cooperating portions of filler 56a and the door front edging 51a are of concavo-convex form for the same reason as indicated above in connection with the top members of the door and doorway. 50

From Figures 15, 16 and 17 it will be seen that the rear edge member 58 of the door and the corresponding wooden door post 59, having insulation 60 applied thereto, are substantially similar to the forward edge and door post members. 55 As clearly shown in Figure 17, the hasping and locking mechanism is modified in that the handle 63 extends substantially longitudinally from the operating rod 64 instead of being bent inwardly towards the face of the door as shown in Figure 10.

Figure 12 shows the application of an insulation strip 61 to the edge of the car floor 62 in position to seal the bottom edge of the doorway when the door is moved inwardly from the partially closed position shown.

Figures 18 to 21, inclusive, show another form of insulation adapted for application to refrigerator cars in particular. It will be seen that the front, rear and top doorway frame members 65, 70 66, and 67 shown respectively in Figures 18, 19 and 20, are provided with curved door opposing flanges 65a, 66a and 67a forming outwardly facing three-sided pockets within which are secured tubular strips of insulation 68, 69 and 70, of 75

rubber or similar material. The Z member 71 at the bottom of the doorway is recessed to form a pocket for receiving the insulating tube 72. The insulating tubes are applied to the doorway 5 frame members by means of bolts 73.

In Figures 22 and 23 are shown somewhat modified forms of swinging retainers corresponding to the retainer hook 24 secured to the forward edge of the door in the first form of the invention described. In Figure 22 the bracket 75, which pivots the hook 77, has a projection 76 adapted to engage the retainer hook to limit the movement of the hook towards the bracket and thereby arrest the outward movement of 10 the door 78. In this form the bearing housing formed of depending door edge members 79 and 80 is substantially wider than the ball cage so that the door has freer transverse movement 15 towards and from the flush position within the doorway than in the previous forms in which the ball will necessarily slide during a portion of the transverse movement of the door.

In Figure 23 the bracket 81 is provided with a hood portion 82 covering the upper portion of 25 the retainer hook 83 and limiting the outward movement of the hook and the corresponding inward movement of the door 84.

In each of the forms of the invention, movement of the door and particularly the trans- 30 verse movement thereof to and from the flush position is substantially easier than has been the case in previous sliding door construction of the flush or inset type. Where substantial play is provided in a transverse direction between the 35 ball bearings and the sides of the bearing housing, transverse movement of the door is easier than where the bearings fit snugly within the housing. Also the door is at all times supported upon the lower track so that the transversely 40 actuating mechanism including rod 34 and cranks 35 and 36 (Figures 1 to 10) carry practically none of the weight of the door even in the closed position, and these members may, accordingly, be made lighter and are less subject to destructive 45 wear than where the whole weight of the door is applied to these cranks during the transverse movement as has been the case in some previous arrangements. Moreover, the location of the various reinforcing gussets, door guides, retainer 50 brackets, and bearings for the operating mechanism so that several of these members may be combined into single rigid or integral structure, substantially simplifies the construction of the door and also permits these parts to mutually 55 reinforce each other.

Flush doors are illustrated, but the invention is generally applicable to inset doors. Other details of the invention may be modified as will occur to those skilled in the art and the exclusive use of all such modifications as come within 60 the scope of the appended claims is contemplated.

What is claimed is:

1. In a door post for a sliding door, an angular section portion extending substantially the length 65 of the post, one leg of said portion facing the doorway and the other leg thereof extending towards the doorway and having an outturned flange with its edge forming a door abutment, a horizontally inclined element at one end of 70 the post for guiding the edge of the door transversely of the post against said abutment, and a strip projecting from said first-mentioned leg and extending therefrom towards the doorway and approximately alined with said inclined element, said strip and flange being arranged to

receive therebetween the edge of the door when moved inwardly along said inclined element to the closed position and to form therewith a weather seal.

2. In combination, a sliding door including 5 an angular edge member with its angle opening outwardly and away from the door body, a door post having a web facing said door and a pair of elements rigidly connected with said web and projecting therefrom towards the doorway, said 10 elements being adapted to receive therebetween the edge of said door when slid against said post and to form with said angular member a pair of substantial weather seal pockets.

3. In combination, a door post, a sliding door, 15 a portion of said post facing the edge of said door, and a member fixed on said post extending substantially the length of said portion and projecting outwardly therefrom and overlying the exterior face of said door and forming a weather 20 seal overlapping the crevice between the door post and the door in its closed position.

4. In combination, a wall having a doorway for a sliding door, brackets extending outwardly from said wall and a track for a rolling door bearing carried on said brackets and including a portion extending abreast of said doorway from side to side of and inside the same and spaced above the lower part thereof.

5. In combination, a wall having a doorway, a 30 bearing track adjacent thereto, and a sliding door mounted on said track and arranged to be moved transversely thereof to a closed position in said doorway, the portion of said track abreast said doorway extending inside the same to support 35 said door in the closed position, said portion being spaced above the lower part of said doorway and forming a weather seal pocket with said doorway part.

6. In combination, a wall having a doorway, a 40 bearing track adjacent thereto, the portion of said track abreast of said doorway extending substantially inside the same and a portion thereof beyond said doorway being spaced from said wall, a sliding door mounted on said track, 45 and means for moving said door transversely on said track to a closed position within said doorway, said means including a retainer straddling the latter mentioned portion of said track.

7. In combination, a wall having a doorway, 50 a bearing track adjacent thereto, a sliding door mounted on said track, the portion of said track abreast of said doorway having a depending flange at its outer edge and the remainder of said track being spaced from said wall, and means for moving said door transversely on said track to and from the position within said doorway and for limiting said transverse movement, said means including a pair of retainers on said track, one of said retainers engaging said flange and 60 the other of said retainers engaging opposite sides of said track.

8. In combination, a wall having a doorway, a horizontal plate adjacent thereto forming a bearing track, a sliding door with a bearing 65 mounted on said track and movable transversely thereon, and a retainer member pivotally secured to said door and overlapping said track to limit transverse movement of said door.

9. In combination, a wall having a doorway, a 70 bearing track with a portion extending inside said doorway, a sliding door having supporting bearings on said track, guide means on said track and door for automatically moving the forward edge of said door transversely on said track 75

- to closed position during sliding of said door, a retainer pivoted to said door adjacent said forward edge and independently of said guide means, and means including a retainer on said 5 track for applying transverse force to the rear edge of said door to move the same transversely on said track to the closed position, both of said retainers cooperating with said track to limit transverse movement of said door.
10. In combination, a sliding door, a bearing track therefor, a retainer for said door comprising a base member attached to said door, and a hook pivoted to said member and extending around a portion of said track, said door being 15 movable laterally on said track and said base member and hook including elements cooperating to limit relative pivoting thereof and to prevent excessive transverse movement of said door.
11. In combination, a doorway with a bearing track adjacent thereto, a sliding door carried on said track by means of rolling bearings, and means independent of said bearings for moving said bearings and said door transversely on said track, said means including a bar pivoted to 20 said door and pivotally mounting an offset retainer member at one end, said member slidably engaging said track and constituting a pivot on said track for said means.
12. Doorway corner construction comprising 25 intersecting frame members, a bearing track for a sliding door adjacent one of said members, and a one-piece metal corner brace for said members including a horizontally inclined element extending transversely of said track for guiding 30 the edge of the door transversely of said track as the door is moved to its closed position.
13. Door corner construction comprising intersecting horizontal and vertical frame members, and a one-piece metal corner brace for connecting 35 said members and having elements at opposite sides of said vertical member for cooperating with an adjacent door guide and for mounting a door retaining member.
14. In a sliding door, intersecting frame members, a bearing housing on one of said members, and a corner gusset for said members including as an integral part thereof a bracket for pivotally 40 mounting a door retainer and an abutment at the
- end of said housing and constituting a bearing stop.
15. In a railway car, a side sill including a horizontal top member, a car side wall above said sill and having a door opening, a car floor resting on said member and terminating short of the outer edge thereof, a track extending alongside of said sill and including a horizontal element projecting over said sill member and spaced thereabove and forming a weather seal pocket therewith, and a door supported on said track and movable into closed position with its inner face abutting the edge of said floor. 5
16. In combination, a wall having a doorway, bearing tracks extending along the horizontal edges thereof, a sliding door carried by at least one of said tracks by means of rolling bearings, means independent of said bearings for moving said door transversely of the doorway to closed position, said means including an operating bar 10 rotatably secured to said door and having offset portions, and retainers movable along said tracks and constituting pivots thereon for said portions. 15
17. In a railway car, a floor, a side wall having a door opening and including a Z-bar door post projecting outwardly beyond the edge of said floor and having its web disposed transversely of the door and its inner flange extending parallel to the door and then bent outwardly with its edge forming a door abutment, said flange and web forming substantially a three-sided weather seal pocket substantially throughout the length of the post and open at the bottom of the post to drain 20 matter collected therein to the exterior of the 25 car. 30
18. In a railway car, a wall having a door opening and including a door post having a part extending transversely of said wall and a portion extending from said part parallel to said wall and then projecting outwardly for a relatively short distance, and a door movable along said wall with its inner face disposed to slide past the outer edge of said door portion and with its front edge disposed to oppose said post part, said post and door forming a substantially closed pocket 40 for preventing the passage of moisture and dirt 45 into the car when said door is closed.

AMBROSE C. MOORE.
AXEL WASBERG.
